UNITED STATES PATENT OFFICE.

WINFIELD SCOTT TURNER, OF PITTSBURG, PENNSYLVANIA, ASSIGNOR OF
ONE-HALF TO ELY WICOFF, OF SAME PLACE.

EXPANSION-JOINT FOR GAS-PIPES.

SPECIFICATION forming part of Letters Patent No. 323,834, dated August 4, 1885.

Application filed May 9, 1885. (No model.)

To all whom it may concern:

Be it known that I, WINFIELD SCOTT TURNER, of Pittsburg, in the county of Allegheny and State of Pennsylvania, have invented a new and useful Improvement in Expansion-Joints for Gas-Pipes; and I do hereby declare the following to be a full, clear, and exact description thereof.

My invention relates to an improvement in expansion-joints for gas-pipes, and has for its object to remedy the evil effects which result from the uneven expansion and contraction of the pipes after they have been joined and laid in the ground. This evil is especially noticeable when gas-pipes are used for the conduction and distribution of natural gas, because this gas comes from the earth in an intensely cold condition, and when it is introduced into freshly laid and connected pipes often causes the latter to contract and break. This has been the cause of a number of destructive accidents which have occurred in those places where natural gas is in common use. The gas escaping from the broken pipe permeates the surrounding soil and enters the cellars of buildings, where it may soon collect in quantity sufficient to produce an explosion. The manner in which inventors have been laboring to avoid these dangers has been principally to render the joints more secure; but while this is desirable and necessary, it cannot overcome the evils of expansion; nor do any of the so-called expansion-joints known to me perfectly meet the requirements of the art.

I will now describe my improvement more particularly, with reference to the accompanying drawings, forming part of this specification, in which—

Figure 1 is a plan view of my improvement. Fig. 2 is a side elevation of the same. Fig. 3 is a vertical section of a single joint.

Like figures and letters indicate like parts. In the drawings, 2 represents a gas-pipe of the kind usually laid in underground trenches and used for the distribution and conduction of gas in cities. These pipes are often of great continuous length, and are therefore subject to considerable extension and contraction by heat and cold. To compensate for this

the pipe is provided with T or elbow joints a' and b', from which a short connecting-pipe, 4, leads to a second connecting-pipe, 5, being joined to the latter by the elbow-joints a and b. The pipe 5 is attached by elbow-joints a' b' to 55 a gas-service pipe, 7, which is a continuation of the main pipe 2. The connections between the elbow-joints a and b, a' and b', and a' and b' are made so that each may turn upon its axis after the manner of a swivel. This is 60 done by screw-threading the adjacent parts and thus uniting them, or by connecting them by a loose sleeve without screw-threading, as at 3, 6, and 8. The consequence is, that the pipes 2 and 7 may be made to approach or 65 recede from each other, just as the two end pieces of a double-jointed carpenter's rule may be moved when arranged parallel with each other. The purpose of the joint at 8 is to allow these pipes to approach in right 70 lines. If it were not there, although they would move longitudinally and turn the joints 3 and 6, that longitudinal movement would also cause them to partake of a swinging side-wise motion, which might prove injurious to 75 the pipes and detract from the benefits of my improved system. When, however, the connection of the pipe 5 with the pipe 7 is swivel-jointed, so as to be capable of rotation on an axis inclined to the axis of the pipes, this side 80 motion is taken up completely by the several joints, and the pipes 7 and 2 suffered to move in perfectly right lines. In order that these joints should act more perfectly, the parts 3, 4, 6, 5, and 8 should be inclosed in a box, 85 which will give them space to move with freedom.

In the description above given it has been supposed that the pipe 2 is closed just beyond the joint 3, and that the pipe 7 is a simple continuation of the former. In such case joints like those shown may be arranged in boxes along the line at suitable intervals; but it is clear that instead of laying the pipe 7 parallel with 2, it may be at a right angle or any other angle 90 therewith, and will in the latter cases act with even greater ease. The consequence is, that my improved joints may be used for branch service-pipes from mains as well as on the mains themselves. This will be clear if the 95 100

pipe 2 be conceived extended, as shown in dotted lines in Fig. 1, and the pipe 7 a branch pipe laid at right angles to the pipe 2.

Thus constructed, when my system of pipes 5 is laid underground and the cold gas introduced, the pipes in shortening will turn the joints 3, 6, and 8, and cause the connecting-pipes 4 and 5 to diverge sufficiently to compensate for the lessened length. If the gas be 10 turned off, the returning heat will expand the pipes and return the swivel-joints into their original positions. The force of contracting and expanding iron is very great, quite great enough to allow the swivel-joints 15 3, 6, and 8 to be screw-threaded, so that leakage at the joints may be easily prevented. It will be found preferable in such case to make the direction of the screw-threads such that the inflow of gas and contraction of the pipes will 20 tighten the joints. They will thus be rendered tighter after use than when first laid.

Fig. 3 illustrates the swivel-joints preferably used by me at the places 3, 6, and 8, being specially designed to prevent leaks. *a* and *b* 25 are two parts which form one of the vertical legs of the elbow connecting the pipes 2 and 4, 5 and 4, or 5 and 7. These pipes are mortised into each other and provided with right-hand screw-threads *c*, by which they are screwed together, as in Fig. 3. The outside periphery of one of the sections is threaded with a right-hand screw-thread, as at *d*, while the other section, *a*, is similarly provided with a left-hand thread at *e*. Over these threaded parts of the 30 sections *a* *b* is screwed a sleeve, *f*, of ordinary construction. On one of the sections, *a*, just back of the end of the sleeve *e*, is made an annular bead or projection, *h*, whose exterior is screw-threaded to the left, and screwed there- 35 to is a sleeve, *i*, which extends over the sleeve *f*, and at the end thereof, on the section *b*, is provided with an annular foot, which is adapted to rest upon the periphery of section *b* of the joint. Suitable packing and washers are 40 interposed between the ends of the parts *a* *b* at *l* and *o*, between the end of the sleeve *f* and the bead *h* at *p*, and at *m* between the sleeve and the foot *k*. An annular washer, *n*, is preferably arranged in a recess in the internal periphery of the parts *ab* and over the 45 joint between their ends.

The parts thus constructed are united and tightened in the way shown in Fig. 3 of the drawings. It will be noticed from inspection 50 of this figure that if the parts *a* and *b* be turned in one direction (say to the left) their ends will be tightened against the packing-rings *l* and *o*, and the bead *h* likewise tightened upon the annulus *p*. If the direction of the parts 55 be reversed, it is clear that the foot *k* will be

drawn against the packing-ring *m*, while the other packings will be slightly loosened. In the application of this joint to the expansion device before described it is so arranged that contraction of the pipes may turn the parts *a* and *b* to the direction whereby the several washers may be tightened. The number of washers and sleeves makes this joint practically gas-tight and does away with all serious danger of leakage, while at the same time it 65 can be turned readily enough for purposes of a rotary expansion-joint.

It will be of course understood that the directions of the threads on the joints just described may be reversed and the same effect 70 produced.

I do not desire to claim, broadly, gas-pipes hinged or pivoted so as to be connected by an extension-joint.

What I claim as my invention, and desire to secure by Letters Patent, is—

1. In a gas-conduit, as a device for taking up expansion and contraction of two connected gas-pipes without breaking connection between the two, the combination of the said 85 pipes and a connecting-pipe joined to each of said gas-pipes by joints which are capable of turning on axes situate on a different plane than the axes of the gas-pipes, substantially as and for the purposes described.

2. In a gas-conduit, as a device for taking up expansion and contraction of two connected gas-pipes without breaking connection between the two, the combination of the said pipes and several connecting-pipes joined to 95 the gas-pipes and to each other by joints capable of turning on axes situate on a different plane than the axes of the gas-pipes, substantially as and for the purposes described.

3. As a rotatory joint for gas-pipes, the 100 combination of a sleeve, *f*, screwing upon an exterior right-hand thread on one of two adjacent sections of pipe and upon a left-hand thread upon the other section, a bead or stop, *h*, on one of the sections, *a*, an exterior sleeve 105 screw-threaded so as to screw upon said bead, and provided with a foot, *k*, which rests upon the other section, *b*, outside of the sleeve *f*, said sections being screwed together with a right-hand screw-thread, and washers for interposing between the ends of said pipe-sections and between the bead and foot and the sleeve *f*, substantially as and for the purposes 110 described.

In testimony whereof I have hereunto set 115 my hand this 4th day of May, A. D. 1885.

WINFIELD SCOTT TURNER.
